(57) **CLAIM**

The ornamental design for a taper candle, as shown and described.

DESCRIPTION

FIG. 1 is a perspective view of a first embodiment of a taper candle of the new design.

FIG. 2 is a front elevation view of the first embodiment of a taper candle of the new design.

FIG. 3 is a rear elevation view of the first embodiment of a taper candle of the new design.

FIG. 4 is a right side elevation view of the first embodiment of a taper candle of the new design.

FIG. 5 is a left side elevation view of the first embodiment of a taper candle of the new design.

FIG. 6 is a top plan view of the first embodiment of a taper candle of the new design; and,

FIG. 7 is a bottom plan view of the first embodiment of a taper candle of the new design.

1 Claim, 3 Drawing Sheets
